UNITED STATES PATENT OFFICE.

CHARLES E. WHITE, OF MOLINE, ILLINOIS, ASSIGNOR TO DEERE & COMPANY, OF MOLINE, ILLINOIS, A CORPORATION OF ILLINOIS.

THRASHING MACHINE.

Application filed September 10, 1918, Serial No. 253,395. Renewed November 13, 1925.

My invention relates to machines for handling small grain such as wheat, oats, etc., and has primarily for its object to provide a power-propelled machine which will take up 5 bundles of grain from the ground as it moves along, and which will be provided with mechanism for severing the heads from the stalks, separating the grain from the heads, and delivering it to a wagon or other receptacle, and with means for discharging the straw. Other objects are to provide mechanism for driving the several operating parts of the machine from the motor which propels the machine, and to provide for steering 10 a machine of this character either by hand or by power-operated mechanism driven from the propelling motor. I accomplish these objects as illustrated in the drawings and as hereinafter described. What I regard 15 as new is set forth in the claims.

In the accompanying drawings:—

Fig. 1 is a plan view of my improved machine, showing a wagon hitched behind it to receive the separated grain;

Fig. 2 is a side elevation thereof;

Fig. 3 is an enlarged detail, being a transverse vertical section on line 3—3 of Fig. 1, some parts being broken away;

Fig. 4 is an enlarged plan view of certain parts of the machine, some parts being broken away;

Fig. 5 is an enlarged partial longitudinal section on line 5—5 of Fig. 1;

Fig. 6 is an enlarged vertical section on line 6—6 of Fig. 3;

Fig. 7 is an enlarged longitudinal section on line 7—7 of Fig. 1, showing the fan and its housing and connections; and

Fig. 8 is a detail, being a partial longitudinal section on line 8—8 of Fig. 2.

My improved machine comprises a main frame mounted on traction wheels at the rear and dirigible wheels at the front, the traction wheels being driven from a suitable motor, such as an internal combustion engine, mounted on the main frame and connected with the traction wheels by means of suitable differential gearing and jack shafts having pinions which mesh with gears on the traction wheels. The dirigible front wheels are arranged to be steered either by a hand operated steering wheel or by power

operated means driven by the propelling motor. The same motor also drives a transverse shaft from which power is transmitted to operate other parts of the mechanism with which the machine is equipped. All these features are not separately claimed herein, as they are fully shown and described in my pending application, Serial No. 231,432, filed April 29, 1918, to which reference is made for the details of the construction and operation of the parts referred to, as it is deemed unnecessary to specifically illustrate and describe them in this application. Such parts are, however, indicated generally in the drawings, 9 indicating the main frame of the machine, 10—11 the traction wheels mounted on spindles 12—13, respectively, 14 one of the dirigible front wheels, the other not being shown as it is hidden by certain parts of the apparatus, 15 the motor, 16 one of the jack shafts, 17 the pinion carried thereby, 18 the gear on the traction wheel 10 with which said pinion meshes, 19 the hand steering wheel, 20 the shaft upon which said steering wheel is mounted, 21 the power operated steering mechanism, 22 the steering rod connected therewith, 23 the transverse power shaft mounted on the main frame, and 24 a transverse bar at the front of the main frame for attachment thereto of other parts of the machine. It will be understood that in addition to the parts illustrated the machine will be provided with change speed gears, levers, and other mechanism for controlling the operation of the machine, as shown and described in my said pending application.

Coming now to the features which more particularly characterize the machine of this application, 25 indicates a transversely disposed bundle carrying frame which is secured to the cross bar 24 in advance of the main frame 9 by hangers 26—27, hinged together at 28, as shown in Fig. 2, so that said transverse frame may be swung up out of operative position when not in use. The left hand side of said frame as viewed in Fig. 1 is of slatted or open-work construction, and the right hand side thereof is floored to provide a platform 29, on which the operator may stand. 30—31 indicate caster wheels at opposite sides of the front

portion of said transverse frame, carried by brackets 32-33, as shown in Fig. 1. 34 indicates a transversely disposed rake which projects forwardly from the frame 25, being 5 suitably hinged thereto at its rear end so that the rake teeth may be raised and lowered by any suitable mechanism under the control of the operator. The points of the 10 rake teeth may be of any suitable construction adapted to ride over the ground to pick up bundles of grain 35. By this construction, as the machine advances, the bundles of grain will be picked up by the rake and will pass back to the frame 25 within 15 easy reach of an operator standing on the platform 29. As the bundles of grain are deposited in rows along the field by the harvester, my improved machine may be propelled across the field, picking up the bundles as it goes along, until the end of the row 20 is reached when the machine may be turned to travel back along the next row by turning the dirigible front wheels either by hand or by power, the caster wheels 30-31, which 25 support the rake frame 25 and rake 34, turning automatically to conform to the turning movement. Ordinarily the hand steering mechanism is employed to guide the machine as it traverses the field, and the power operated steering mechanism is used in turning 30 the machine at the ends of the rows.

36 indicates a hopper mounted on the main frame 9 back of the inner portion of the frame 25, as shown in Fig. 1. This hopper is of suitable size and shape to receive a bundle of grain disposed transversely of the machine, and extending longitudinally in the bottom thereof is a beater drum 37 having teeth 38 as usual. Said drum is divided 25 transversely into sections mounted upon a shaft 39 which extends transversely of the machine. Between the sections of the beater drum, said shaft carries circular saws 40—41 of somewhat greater diameter than the 40 drum, as shown in Fig. 3 and Fig. 5. The saw 41 serves the purpose of severing the heads from the stalks, while the saw 40 cuts the straw into shorter sections. The beater drum serves the purpose of breaking up the 45 straw to facilitate its discharge from the machine in the manner hereinafter described.

42 indicates an auxiliary hopper arranged opposite the inner end of the hopper 36 to receive the severed heads of the grain when they are cut off by the saw 41, said auxiliary hopper being best shown in Figs. 1, 4 and 5. The latter hopper discharges into a cylindrical separator chamber 43, formed by housing members 44-45, which chamber is arranged back of the hopper 42 and contains a beater drum 46 having teeth 47 which contact with the fingers 48 of a concave having gratings 49 through which the separated grain may pass into a conveyer duct 50, as shown in Fig. 5. This duct is secured at the

under side of the housing member 45 and extends back and up to a discharge tube 51 which is adapted to deliver the separated grain to a wagon 52, attached to the rear of the main frame 9, as shown in Fig. 2. 53 indicates an exhaust tube or flue for the chaff which communicates with the rear portion of the chamber 43, as shown in Fig. 5, and extends back over the conveyer duct 50 to a return flue 54, which connects with the 75 housing 55 of a fan 56, best shown in Figs. 2 and 7. The exhaust tube 53 is made zig-zag in shape, as shown in Fig. 5, its inner angles being connected to the conveyer duct 50, as shown in said figure, and being provided with gratings 57, through which grain may pass into said duct. At its outer or upper angles, it is provided with rock shafts 58, carrying fingers 59, which traverse the path of the chaff and act as flails to break up the mass of chaff to permit any grain carried thereby to separate and pass out through the gratings 57 into the conveyer duct. The position of the fingers 59 may be adjusted by rocking the shafts 58, for which purpose said shafts are provided with cranks 60 at their outer ends, as shown in Fig. 2. A series of stops 61 is also provided for setting the cranks 60 in different positions of adjustment, as shown in said figure. 95

The grain which falls into the conveyer duct 50 is carried up to the discharge tube 51 by means of an endless conveyer 62 having transverse slats 63, as shown in Fig. 5. Said conveyer is mounted upon sprocket 103 wheels 64-65, carried by transverse shafts 66-67, arranged to rotate so that the lower portion of the conveyer travels upward, as indicated by the arrow in Fig. 5.

The several parts of the mechanism above described are driven from the transverse shaft 23 by the following mechanism: 68 indicates a belt which is driven by a pulley 69 mounted on one end of the shaft 23, as shown in Figs. 1 and 2, which belt drives a pulley 70, mounted on a transverse shaft 71 which carries the fan 56, as shown in Figs. 2 and 3. The conveyer 62 is driven from the shaft 71 by means of a worm 72 carried by said shaft, which meshes with a worm wheel 73 mounted on a shaft 74 which extends longitudinally of the conveyer duct 50, as shown in Figs. 2 and 8. At its upper end, the shaft 74 carries a beveled pinion 75, which meshes with a beveled gear 76, carried by the shaft 66, as shown in Fig. 8. Thus, when the shaft 71 is rotated, the conveyer 62 is driven in the direction indicated by the arrow in Fig. 5. The beater drum 46 is mounted on and keyed to the shaft 71, as shown in Figs. 3 and 5, and consequently rotates therewith. The shaft 39, which carries the beater drum 37 and saws 40-41, is driven from the shaft 71 by means of a gear 77 mounted on the inner end portion of the shaft 71, as shown in 130

Fig. 3, and meshes with a pinion 78 mounted on the inner end of the shaft 39, as shown by dotted lines in Fig. 5. The shaft 39, therefore, rotates in a direction opposite to that of the shaft 71.

In order to sever the twine or wire by which the bundles of grain are bound, I provide a rotating knife 79, preferably two-bladed, which is mounted upon the upper end of a shaft 80 arranged back of the hopper 36 in such position that the blades of the knife rotate in a plane which extends longitudinally of the hopper, the knife blades projecting through a longitudinal slot 81 in the back of the hopper, as shown in Figs. 1 and 3. The shaft 80 is driven from the shaft 71 by means of a beveled gear 82, mounted on the lower end of said shaft, as shown in Figs. 3 and 5, and meshing with a beveled pinion 83 at the inner end of the shaft 71. Thus, the knife 79 is constantly rotated when the machine is in operation.

84 indicates a discharge flue leading from the fan housing 55 and extending longitudinally of the lower portion of the hopper 36, as shown in Fig. 3, with which it communicates laterally at a point below the level of the axis of the beater drum 37, as best shown in Fig. 6. The flue 84 is provided with a discharge nozzle 85, as shown in Fig. 3, through which the broken-up straw which passes into said flue from the hopper 36, is blown out at one side of the machine. 86 indicates the driver's seat which, as shown in Fig. 2, is mounted on the main frame 9 conveniently with reference to the steering wheel 19.

The operation of the machine will, no doubt, be readily understood from the foregoing description, but for convenience it may be recapitulated as follows: The machine is driven across the field and guided by the driver by means of the hand wheel 19 so as to pick up the bundles of grain as it goes along. Meanwhile, another operator, standing on the platform 29, tosses the bundles into the hopper 36 with the heads toward the inside end thereof. The binding twine is immediately severed by the knife 79 and the stalks are cut transversely by the saws 40-41 into two or more pieces, depending upon the number of saws provided. The heads then drop through the auxiliary hopper 42 into the separator chamber 43 while the straw is broken up by the beater 37. When the machine is in operation, the rotation of the fan 56 creates suction in the tube 53 through flue 54, and consequently the chaff liberated by the action of the beater cylinder 46 is drawn out through said tube and returned through flue 54 to the discharge flue 84 where it passes out together with the straw through nozzle 85. The greater part of the grain separated by the

action of the beater cylinder 46 passes out through the gratings 49 into the conveyer duct 50, in which it is carried up by the endless conveyer therein to the spout 51, through which it is delivered to the bed of the wagon 52. Any grain that may pass up through the tube 53 with the chaff is ultimately separated therefrom, not only by the action of the fingers 59 which break up any masses of chaff that may be formed, but also by reason of the shape of said tube, which prevents the too rapid passage of the chaff through it, and provides a number of valleys or depressions calculated to gather the freed grains and permit them to pass to the conveyer duct through the gratings 57. Just before the machine reaches the end of the row, the power operated steering mechanism is brought into operation, so that the machine turns about a predetermined radius and travels back in the opposite direction.

It should be understood that while I have described in detail the specific embodiment of my invention illustrated in the drawings, the claims hereinafter made are not to be restricted to such specific construction as many of the features are generically new and the claims thereto are to be construed accordingly.

What I claim as my invention, and desire to secure by Letters Patent is:

1. A thrashing machine comprising means for severing the heads of the grain from the straw, thrashing mechanism, means for delivering the heads to said thrashing mechanism, means for discharging the straw, and suction mechanism operating to deliver the chaff to the straw.

2. A thrashing machine comprising a hopper adapted to receive bundles of grain, means operating in said hopper to sever the heads from the straw, thrashing mechanism arranged to receive the severed heads and operating to separate the grain from the chaff, means associated with said hopper for discharging the straw, a conveyor for the separated grain, and a flue for the chaff extending over said grain conveyor and communicating at intervals therewith.

3. A thrashing machine comprising a hopper adapted to receive bundles of grain, means operating in said hopper to sever the heads from the straw, thrashing mechanism arranged to receive the severed heads and operating to separate the grain from the chaff, means associated with said hopper for discharging the straw, a conveyor for the separated grain, a flue for the chaff extending over said grain conveyor and communicating at intervals therewith, said flue being arranged to conduct the chaff to the straw, and means for maintaining a current of air through said flue.

4. In a thrashing machine, the combination with a frame having traction and steer-

ing wheels, and a motor carried by said frame, of thrashing mechanism carried by said frame, mechanism operated by said motor for driving said thrashing mechanism and propelling the machine, means connected with said frame and extending forward therefrom for carrying bundles of grain, and means operated by said motor for steering the machine.

5 10 5. In a thrashing machine, the combination with a frame having traction and steering wheels, and a motor carried by said frame, of thrashing mechanism carried by said frame, mechanism operated by said motor for driving said thrashing mechanism and propelling the machine, racking means connected with said frame and extending forward therefrom for taking up bundles of grain from the ground, and means operated by said motor for steering the machine.

15 20 6. A thrashing machine comprising a main frame, a motor carried thereby, traction means operated by said motor for propelling the machine, means connected with said frame for carrying bundles of grain, a hopper adjacent to said bundle-carrying means, means operating in said hopper for severing the stalks of grain transversely, means for driving said severing mechanism from said motor, thrashing mechanism carried by said frame and means for delivering the heads of the grain to said thrashing mechanism.

25 30 35 7. A thrashing machine comprising a main frame, a motor carried thereby, traction means operated by said motor for propelling the machine, means connected with said frame for carrying bundles of grain, thrashing mechanism carried by said frame, a hopper adjacent to said bundle-carrying means and communicating with said thrashing mechanism, means driven by said motor for severing the heads of the grain in said hopper and means for delivering the heads of the grain to said thrashing mechanism.

40 45 50 55 8. A thrashing machine comprising a main frame, a motor carried thereby, traction means operated by said motor for propelling the machine, means connected with said frame for carrying bundles of grain, thrashing mechanism carried by said frame, a hopper adjacent to said bundle-carrying means and communicating with said thrashing mechanism, means driven by said motor for severing the heads of the grain in said hopper, means for delivering the heads to said thrashing mechanism, and means for driving said thrashing mechanism from said motor.

60 65 9. A thrashing machine comprising a main frame, a motor carried thereby, traction means operated by said motor for propelling the machine, bundle-carrying means connected with said frame, thrashing mech-

anism carried by said frame, a hopper communicating with said thrashing mechanism, means for severing the heads of the grain in said hopper from the stalks, means for delivering the heads to said thrashing mechanism, and means for breaking up the severed stalks.

70 10 15 10. A thrashing machine comprising a main frame, a motor carried thereby, traction means operated by said motor for propelling the machine, bundle-carrying means connected with said frame, thrashing mechanism mounted on said frame, a hopper communicating with said thrashing mechanism, a beater cylinder below said hopper, means for severing the heads of the grain in said hopper from the stalks, means for delivering the heads to the thrashing mechanism, and means for driving the several operating parts mentioned from said motor.

75 80 85 11. A thrashing machine comprising a main frame, a motor carried thereby, traction means operated by said motor for propelling the machine, bundle-carrying means connected with said frame, thrashing mechanism mounted on said frame, a hopper communicating with said thrashing mechanism, means for severing the heads of the grain in said hopper from the stalks, means for delivering the heads to said thrashing mechanism and means operated by said motor for discharging the straw from said hopper.

90 95 100 12. In a thrashing machine, the combination with a main frame, a motor carried thereby, traction means operated by said motor for propelling the machine, and bundle-carrying means connected with said frame, of thrashing mechanism mounted on said frame, said thrashing mechanism comprising a duct for receiving and conveying the separated grain, a flue for receiving the chaff, and a fan for applying suction to said flue, and means for driving said thrashing mechanism from the said motor.

105 110 115 13. In a thrashing machine, the combination with a main frame and thrashing mechanism mounted on said frame, said thrashing mechanism comprising a duct for receiving and conveying the separated grain, of a flue extending over said duct and having valleys communicating with said duct, and means for causing chaff to flow through said flue.

120 125 130 14. In a thrashing machine, the combination with a main frame and thrashing mechanism mounted on said frame, said thrashing mechanism comprising a duct for receiving and conveying the separated grain, of a flue extending over said duct and having valleys communicating with said duct, and a fan for applying suction to said flue to cause chaff to flow therethrough.

15. In a thrashing machine, the combination with a main frame and thrashing mechanism mounted on said frame, said thrashing

mechanism comprising a duct for receiving and conveying the separated grain, of a zig-zag flue extending over said duct, the valleys of said flue communicating with said duct, and means for causing chaff to flow through said flue.

16. In a thrashing machine, the combination with a main frame and thrashing mechanism mounted on said frame, said thrashing mechanism comprising a duct for receiving and conveying the separated grain, of a zig-zag flue extending over said duct, the valleys of said flue communicating with said duct, and a fan for applying suction to said flue to cause chaff to flow therethrough.

17. In a thrashing machine, the combination with a main frame, a motor carried thereby, traction means operated by said motor for propelling the machine, and bundle-carrying means connected with said frame, of thrashing mechanism mounted on said frame, said thrashing mechanism comprising a duct for receiving and conveying the separated grain, a zigzag flue for receiving the chaff, and a fan for applying suction to said flue, and means for driving said thrashing mechanism from said motor.

18. In a thrashing machine, the combination with a main frame, a motor carried thereby, traction means operated by said motor for propelling the machine, bundle-carrying means connected with said frame, a hopper adapted to receive a bundle of grain, and means for severing the heads of the grain in said hopper from the stalks, of thrashing mechanism mounted on said frame and communicating with said hopper, said thrashing mechanism comprising means for separating the grain from the chaff, a duct for receiving and conveying the separated grain, a flue for the chaff, a fan connected with said flue for creating suction therein, and a discharge flue connected with said hopper and with said first mentioned flue for discharging the chaff and straw, and means

for driving said thrashing mechanism from said motor.

19. In a thrashing machine, the combination with a main frame, a motor carried thereby, traction means operated by said motor for propelling the machine, bundle-carrying means connected with said frame, a hopper adapted to receive a bundle of grain, means for severing the heads of the grain in said hopper from the stalks, and means below said hopper for breaking up the straw, of thrashing mechanism mounted on said frame and communicating with said hopper, said thrashing mechanism comprising means for separating the grain from the chaff, a duct for receiving and conveying the separated grain, a flue for the chaff, a fan connected with said flue for creating suction therein, and a discharge flue connected with said hopper and with said first mentioned flue for discharging the chaff and straw, and means for driving said thrashing mechanism from said motor.

20. In a thrashing machine, the combination with means for separating grain from the chaff and means for delivering heads of grain thereto, of a duct for receiving and conveying the grain, a zigzag shaped flue for the chaff extending over said duct, gratings at the valleys of said flue communicating with said duct and means for causing the chaff to flow through said flue.

21. In a thrashing machine, the combination with means for separating grain from the chaff, and means for delivering heads of grain thereto of a duct for receiving and conveying the grain, a zigzag shaped flue for the chaff extending over said duct, gratings at the valleys of said flue communicating with said duct, means in the elevated portions of said flue for breaking up masses of chaff, and means for causing the chaff to flow through said flue.

CHARLES E. WHITE.
